UNITED STATES PATENT OFFICE.

THOMAS COOK, OF STALYBRIDGE, AND HENRY THEOPHILUS JOHNSON AND JAMES EDWARD THOMAS FOOT, OF LONDON, ENGLAND.

BALING-MACHINE.

1,259,961.

Specification of Letters Patent. Patented Mar. 19, 1918.

Application filed June 26, 1917. Serial No. 177,135.

To all whom it may concern:

Be it known that we, THOMAS COOK, HENRY THEOPHILUS JOHNSON, and JAMES EDWARD THOMAS FOOT, subjects of the King 5 of Great Britain and Ireland, and residents respectively, of Stalybridge, in the county of Chester, London, in the county of London, and London, in the county of London, England, have invented certain Improvements to 10 Baling-Machines, of which the following is a specification.

This invention relates to improvements in baling presses or machines and is adapted to compress into bales of any suitable dimensions, paper, cotton, wool, hay, metal turnings, borings or the like and generally waste or other materials of or from manufacturers capable of or requiring to be compressed into small compass, our object being 20 to provide a powerful press of simple construction which can be operated entirely by hand or partly by hand and power or by power alone.

With the aforesaid objects in view our invention comprises a press box having a 25 hinged cover to form the top of the box and a hinged door at one side or end, a ram within the box operated by a chain or cable gear conveniently connected to it and to driven 30 pulleys, preferably of the fusee type, said fusee pulleys being arranged to exert a gradually-increasing pressure upon the material being compressed as said material increases 35 in density, fusee and chain or cable gear for returning the ram to initial position after the compressing operation and means for driving the various parts of the press.

Our invention will be fully described with 40 reference to the accompanying drawings in which,

Figure 1. is a side elevation of so much of our improved machine as is necessary to illustrate the essential features of our invention,

Fig. 2. plan of same,

Fig. 3. longitudinal side elevation in section and

Fig. 4. transverse section of the machine on line 1—2 of Fig. 3.

50 In carrying out our invention, which is shown as a horizontal press though with

slight modifications it may be arranged vertically, we provide a press box *a* of convenient form and dimensions, which may be supported at its inner end by the main headstock framing *b* and at its outer end by a foot *c*. In the drawings the box *a* is shown of semi-circular form such as we use when compressing metal turnings, borings or the like into cylindrical form, the top section 60 of the box being completed by a cover *d* of substantially semi-circular cross section, pivoted on shaft *e* which is bent at one end *f* to carry counterweights *g* or is provided with a separate arm secured to the shaft and carrying weights as aforesaid, said weights controlling the raising and lowering of the cover out of and into working position within the box. A handle *h* is used to assist in the operation. The end of the press box 70 may be solid, as shown in Fig. 3, or it may be adapted to be hinged to enable the product compressed to be removed, but we prefer to make it solid as indicated and to employ a hinged side door *i* which can be turned down 75 to remove the product from the box. Normally the door *i* is held in position by means of a catch lever *j* pivoted at *k* and arranged to engage with a catch *m* at the end of the box and with the side of the box at *n* for 80 the purpose of holding the lever *o* pivoted at *p* passing up the end of the box and over the top where it terminates in a handle *q*. To the handle portion is pivoted a short lever *r* carrying a pulley *s* which rests upon the 85 cover *d* as shown in Fig. 3.

In conjunction with the press box we employ a ram provided with a head *t* secured at one end of a long plunger *u*, the other end of which is supported at the right height by 90 a downwardly projecting arm *u'* in which is journaled a roller *v* running upon the floor or upon a rail *w* or track fixed thereto. The longitudinal movement of the ram for compressing purposes is carried out by means of 95 cables or chains *x*, one end of each of which is secured at the largest diameter of fusee pulleys *y* fixed upon a shaft *z* journaled in the headstock framing *b*, the cables being passed over guide pulleys *2* also mounted 100 upon a shaft or studs *3* carried by the framing *b*. The cables pass rearwardly from the

5 fusees over pulleys 4 mounted upon the ends of a transverse arm 5 pivoted at its middle part by a vertical pin 40 to the rear end of the ram so that said arm may have a compensating movement about the pivotal center to keep the two cables in an equal state of tension. The cables pass from the underside of the pulleys 4 over the guide pulleys 2 and then rearwardly to eye-bolts 6 to which 10 are coupled screwed adjusting rods 7 passing through blocks 8 carried by or forming part of the arm 5, such arrangement enabling the cables to be adjusted as required. The fusee shaft α is driven by a train of gear wheels 9 15 from the main operating shaft 10 of the machine upon which is located a pair of fast and loose pulleys 11 and which has fixed upon it a pinion 12 forming the first member of the gear train. It will, therefore, be seen 20 that the operation of the chain, spur wheel, fusee and cable gear forces the ram forward to compress the material which is placed in the press box by first lifting up the cover d to admit it and closing such cover and 25 locking it in position. It will also be observed that when the ram is at the rearward end of its stroke the material is in comparatively loose condition with the fuses acting upon the cables at their largest diameters. 30 As the fusees rotate and the ram advances the cable is acted upon by a gradually-decreasing leverage of the fusee and consequently the greatest power can be exerted upon the ram at the time the compressed 35 material arrives at its maximum density. The ram may be arranged to cause the driving belt to slip on the driving pulley as the maximum pressure is exerted when the machine can be stopped by hand or, preferably, 40 we arrange the ram to automatically stop the machine at a definite point in its traverse. To this end we mount upon the upper side of the ram an adjustable inclined plate 13 adapted to engage with a pulley or roller 45 14 carried at the lower end of a slideable rod 15. The upper end of the rod 15 is operatively connected with the horizontally slideable bar 16 of the belt fork 18. The bar 16 slides in guide brackets 17, and when the rod 50 15 is pushed upwardly the belt fork 18 shifts the driving belt from the fast to the loose pulley. If desired the shaft 10 may have fixed upon the opposite end to the pinion 12 a ratchet wheel α' engaging with a pivoted 55 pawl α'' to hold the parts, including the ram, in the position to which it has been moved and prevent the ram being forced backward by the resilience of the material compressed. By releasing the pawl the said 60 material may act to partially return the ram for a very short distance but for the purpose of positively returning the ram to initial position we employ a third fusee 19 fixed upon shaft α to which is connected one end

of a cable 20. The cable is passed from this 65 fusee around the pulley 21 carried by the ram, its end being taken rearwardly and secured to a clamp 22 which, in turn, is coupled to a rod 23 anchored to a spring 24, the frame 25 upon which the spring is mounted being coupled to an adjustable rod 25' secured to a bracket 26. By rotating the driving shaft in the opposite direction the third cable draws the ram rearwardly as it coils upon its fusee and at the same time the 75 compressing cables are unwound from their fusees when the machine is ready for the next operation.

We also provide means for checking the momentum of the geared parts of the machine as the ram is being returned to initial position for the purpose of preventing overrunning of the ram in a backward direction. For this purpose we fix on shaft 10 brake drum 27 against which a brake block 28 can 80 be pressed. This block is fixed on one arm 30 of a belt crank-lever 29 pivoted on the frame stay 31, the other arm 32 passing downward into the path of a stud 33 adjustable longitudinally along the ram. 85 When the latter is traversing rearwardly the stud 33 engages arm 32 and forces the brake block 28 against the brake drum 27, thus stopping the machine. 90

We would have it understood that in place 95 of the three fusees we may employ ordinary cylindrical pulleys upon which the chains are wound or unwound, but we prefer the fusees particularly in connection with the compressing mechanism for the reason already stated. 100

Having now particularly described and ascertained the nature of our said invention and in what manner the same is to be performed, we declare that what we claim is:— 105

1. In a baling press, a press chamber formed of two longitudinal parts, the upper part having its front end pivoted to the lower part and being movable, a lever pivoted at one end below the lower part of the 110 press chamber at the rear end thereof and extending upwardly across its rear end and projecting forwardly over the rear end portion of the movable part, and a bell-crank locking lever pivoted to the upper end portion of the aforesaid lever and adapted to bear on the said movable part. 115

2. In a baling press, a press chamber, a ram slideable therein, a revoluble driving shaft, intermediate driving mechanism for sliding the ram in the press chamber when the driving shaft is revolved, a brake drum secured on the driving shaft, a pivoted brake lever provided with a brake block for bearing on the brake drum, and means for operating 120 the said brake lever from the ram at a predetermined point of its travel to check the motion of the said driving mechanism. 125

3. In a press for the purposes referred to, the means for checking the momentum of the geared parts of the machine, comprising a brake drum on the power shaft, a 5 brake block adjacent thereto, a pivoted lever one arm of which carries the brake block while the other arm depends alongside the press ram and an adjustable stud on the press ram to contact with the arm.

In testimony whereof we have hereunto 10 set our hands in the presence of two witnesses.

THOMAS COOK.

HENRY THEOPHILUS JOHNSON.

JAMES EDWARD THOMAS FOOT.
